UNITED STATES PATENT OFFICE.

ARTHUR SPEAR, OF CHICAGO, ILLINOIS.

NUT-CASTELLATING MECHANISM.

Application filed March 26, 1920. Serial No. 369,117.

To all whom it may concern:

Be it known that I, ARTHUR SPEAR, a citizen of the United States, and resident of Chicago, in the county of Cook and State of Illinois, have invented certain new and useful Improvements in Nut-Castellating Mechanism, of which the following is a specification.

My invention relates to improvements in punch presses and has special reference to improvements in means and methods for producing castellated nuts.

The rapid and wide development of the automobile has greatly increased the demand for screw nuts which are made to be held against loosening by a split cotter, which extends through the end of the bolt on which the nut is received and is received in notches provided in a crown on the nut. Such nuts on account of their appearance are commonly called castellated nuts. The great quantities of these nuts which are now used has led to the necessity of improved and automatic means for producing the notches in the crown. In order to be able to hold the nut tightly against the abutment against which it is screwed in use, it has been found desirable to provide hexagon nuts with at least three diametri-

cally arranged pairs of the notches, making six notches in all, one in each side of the nut and by means of my improved multiple punch press and automatic feed I am enabled, upon each stroke of the press, to eject one completely castellated nut; as I punch six notches in six separate nuts at each stroke of the punch and feed the nuts through the machine from one punch to the next, step by step, cutting a notch in each of the nuts at each step.

I have found that it is productive of best results, particularly as regards the bore of the nut, that the punch or cutter should cut outwardly from the bore of the nut through the wall of the crown, and I have provided a punch of very simple construction and very simply operated for operating on the nut in this manner. I provide a swinging blade or tool holder so pivotally mounted and so related to the die on which the nuts are held that I am enabled to mount the device upon an ordinary punch press and cause the punches to swing up and down, the end of the punches swinging into the bores of the nuts and cutting outwardly against the die upon which the nuts rest.

This swinging die is linked by a very simple lost motion device to the vertically movable head of the press so that regardless of the amount of movement of the head the 60 swinging punch only moves up and down through the desired arc.

I provide a very simple feed device for automatically feeding the nuts from the initial position where one notch is produced 65 through the successive positions where the successive notches are produced until the nut is finally discharged from the device with the six notches cut therein, that is, in completely castellated form.

The feed device is also connected with the vertically movable head of the press and is operated automatically thereby. As the nuts are moved along by the feed device they are automatically rotated step by step, being 70 turned a sixth of a revolution at each step so that as the multiple punch swings down the notches produced by the several cutters are produced in the successive sides of the nuts.

My invention will be more readily understood by reference to the accompanying drawings forming part of this specification and in which:—

Figure 1 is a front elevation of the device, 85 shown connected to the vertically movable head of a punch press,

Figure 2 is a side elevation of the device,

Figure 3 is a horizontal section on the line 3—3 of Figure 2, and 90

Figure 4 is a vertical section on the line 4—4 of Figure 2.

In said drawings 1 represents the base of a punch press, and 2 represents the vertically movable head of the punch press. The base 95 1 serves as a support upon which the die device is secured and the head 2 carries the movable mechanism for supplying power to the punching device.

My improved nut castellating or punching mechanism comprises a base plate 3 adapted to be secured to the base 1 of the punch press in position below the head 2 and carries a vertically swinging punch or cutter holder 4 mounted to swing on a horizontal axis on bearings 5 at the end of the holder 4 which bearings are rotatably mounted in suitable openings in vertical standards 6 rising from the ends of the base plate 3. The holder 4 is provided 110 with a plurality of vertical transverse slots 7 opening through its upper face for re-

ceiving cutters 8 by which the slots are cut in the nuts. I provide six of these slots and six cutters and all of the cutters are held firmly in position by a single top plate 9 secured to the holder by means of screws 10. The cutters 8 are thin strips of steel somewhat similar to cut-off tools except that they have parallel sides and they are adapted to be advanced from time to time through 10 the slots 7 to properly position their forward ends 8' in relation to the nuts as they are ground back for sharpening them.

The holder 4 is swung up and down by means of a head member 11 secured to the 15 vertically movable member 2 of the punch press. I connect the holder 4 to the head 11 by a lost motion connection which permits the head 11 to move up and down the full motion of the vertically movable member 2 of the punch press and which permits the head 4 to move up and down sufficiently to perform the operation of cutting the slots in the nuts without limiting the vertical movement of the head 11. This 20 lost motion connection between the two members consists of slotted links 12 pivotally connected at their lower ends to the holder 4 by screws 13 and connected at their upper ends to a block 14 carried on the 25 lower end of a vertical guide pin 15 which extends through a suitable central opening 16 in the head 11 and is provided on its upper end with an enlarged head 17 adapted to seat on a shoulder 18 in the head 11 to 30 limit the downward movement of the block 14. The block 14 is of equal length with the holder 4 and to prevent the block 14 from swinging round horizontally out of alignment with the holder 4 I provide a 35 guide projection 19 on the head 11 against which one vertical face 20 of the block 14 is always in contact. The upper ends of the links 12 are provided with slots 21 for securing screws 22 so that the block 20 will 40 have some free up and down movement relative to the holder 4 for properly contacting with the holder 4 in the operation of pressing the head downwardly to cut the nuts. In Figure 2 I have shown the block 14 at 45 the upper limit of its movement and the head 11 at the upper limit of its movement. It will be obvious upon examining said figures that the head 11 is free to descend toward the holder 4 some distance before it 50 will contact with the upper surface of the block 14 to force same down. During this part of the movement the enlarged head 17 on the guide rod 15 is rising through the bore 23 in the head 11. It will be obvious 55 that in addition to the guide projection 19 or independently thereof I may provide the block 14 with guide pins 24 adjacent to its ends and rising through guide openings in the head 11 for preventing the block 14 60 swinging round on the connecting pin 15.

The machine as designed is adapted to cut slots in the crowns 25 of hexagon nuts 26 and for properly positioning these nuts in relation to the cutters 8 for cutting slots 27 in the nuts I provide a die or combined 70 die and nut holding member comprising a series of die blocks 28 positioned in the path of the forward ends of the cutters 8 and each provided with a die slot 29 to permit the cut out portions to drop free of the device. The several blocks 28 are mounted upon the base 3 and are removably held in position by screws 30 at the ends of the base 3 having flanges 31 engaging the ends of the outer blocks. These blocks rest at their 80 rear sides against a vertical flange 32 rising from the base 3 and are held rearwardly and securely against this flange by an angle member 33 having a vertical flange 34 positioned against the faces of the blocks 28 85 and a horizontal flange 35 resting upon the upper face of the base 3 and secured to the base by screws 36.

The nuts 26 are fed to the machine through a chute 36 arranged at one end of 90 the machine, and the nuts drop down upon the upper surfaces 37 of the several die blocks 28 which are arranged in a single plane. The nuts are spaced on this surface and moved along by a feeding device which 95 will be more fully described hereinafter. The nuts are positioned by the feeding device centrally above the several die slots 29 as best shown in Figure 4 and are accurately positioned in relation to said slots by pressure blocks 38 arranged one above each die slot and yielding held downwardly by compression springs 39 which are mounted in pockets 40 in said pressure blocks and bear at their upper ends against a relatively 100 fixed flange or plate 41 rigidly secured to a rigid wall 42 rising from the base plate 3. These pressure blocks 38 are held against the front face of the wall 42 by a cover plate 42' and screws 43 which enter into the 105 wall 42 through slots 44 provided in the adjacent edges of the blocks 38. The downward movement of the blocks 38 is limited by the screws 43 which are arranged to contact with the upper ends of the slots 44 to 110 prevent the blocks 38 being forced downwardly by the springs 39 too far. Each block 38 is provided, in its lower end, with a wide notch 45, adapted, as best shown in 115 Figure 4, to receive one of the side faces of 120 a nut 26 and position it accurately over the slot 29 below same.

The nuts 26 are positioned with their crowned ends toward the cutter holder 4 and the cutter holder is so placed upon the 125 bearings 5 in relation to the height of the upper surface 37 of the die-blocks 28 upon which the nuts 26 rest that the forward ends 8' of the cutters 8 can swing into the bores 46 of the nuts 26, entering at the upper 130

edges of the bores and swinging rearwardly into the bores far enough to cut the desired depth of notch 27 in the crown of the nut.

As explained hereinbefore I provide positions for six of the hexagon nuts and six of the cutters 8 and as the holder is depressed each cutter cuts a notch 27 in one of the six nuts. In other words, six notches are cut at each downward movement of the holder 4 and at each movement of the feed device the nuts are progressively moved through the machine from one position to the next, so that at each forward movement of the feed device one additional blank nut is fed into the machine and one finished nut is discharged.

The feeding device comprises a longitudinal plate 47 which is arranged in horizontal position at the rear of the nuts in a horizontal slot 47' provided in the wall 42. This plate is provided on its forward edge with nut engaging projections 48 for moving the nuts along upon their sides from one position to the next and for rotating the nuts in such movement. I provide seven of these projections 48 one for each of the nuts being operated upon and one for engaging a blank nut for feeding it into the machine. This plate 47 is movable longitudinally of the device for feeding the nuts along and is movable transversely of the device for engaging and disengaging the nuts. The mechanism which I provide for moving this feed plate comprises a pair of swinging levers 49 pivotally mounted on a flange 50 of the base member 3 and connected together for simultaneous movement by a horizontal link 51 pivotally connected at its end to the levers by pivot pins 52. At the center of this link I provide a fixed horizontal pin 53 which is received in a cam slot 54 in a vertically movable cam bar 55 rigidly secured at its upper end to the rear face of the head 11 by bolts 56.

The upper ends 57 of the levers 49 are received in inclined slots 58 in the feed plate 47 and are provided with anti-friction rollers 59 to reduce friction. The inclined slots 58 are so arranged that upon the beginning of the forward movement of the levers 49 the plate 47 is advanced to cause the projections 48 to engage the rear sides of the several nuts, and as the levers swing forward the plate 47 is moved longitudinally of the device and each of the several nuts is moved from one position to the next. In such movement of the nuts the forward walls 60 of the several notches 45 in the pressure plates 38 engage the adjacent corners of the nuts and cause them to be rotated from one face to the next face in the direction of the arrow 61 on Figure 4 so that they will be presented to the next cutter in the series in proper position to have the next slot cut. To avoid any interference

between the lower corners of the pressure-plates 38 with the nuts as they are advanced I bevel or round off the rear lower corners 38' of these plates so that even if one plate should project below the adjacent plate the nut as it advances will not be caught by the corner but will cam the plate up out of its path.

In such movement of the nuts they slide forward upon the forward portion 28' of the die blocks 28 which are enough higher than the rear portions of the blocks to provide a channel 28" in which the corners of the nuts can freely turn as the nuts slide along upon the outer peripheries of their crowns.

As explained hereinbefore, the first part of the downward movement of the head 11 causes the levers 49 to swing forward thus causing the feed plate 47 to be advanced to engage the projections 48 with the nuts. The continued downward movement of the head 11 causes the feed plate to be advanced to advance the nuts from one position to the next and at the point that the lost motion between the head 11 and the block 14 is all taken up when the block 14 pushes down the cutter holder 4 the cam pin 53 has reached the vertical portion 62 of the cam slot 54 so that the feed plate 47 at such time remains stationary. In reverse operation the plate 47 remains stationary during the period that the cam bar is rising with the cam pin 53 in the vertical portion 62 of the cam slot and as the cam pin travels through the inclined portion of the cam slot the swinging levers 49 begin to swing in the opposite direction. At the initial portion of their movement their upper ends by moving through the inclined slots 58 in the feed bar draw the feed bar rearwardly out of engagement with the nuts and then they move the plate 47 longitudinally to the position shown in full line in Figure 3 ready for the next cycle of operations.

It is to be noted that the block or head 14 rests at all times in contact with the forward and upper edge of the plate 9 which holds the cutters in the holder 4 and being in contact therewith it does not strike the plate a blow in beginning the pressing operation, but merely presses the same down. The holder 4 is normally held at the upper limit of its movement in contact with the block by suitable compression springs 63 mounted in the pockets 64 provided in the base 3 and having their upper ends mounted in suitable pockets 65 in the lower wall of the holder 4.

For the purpose of producing a slight friction on the feed plate 47 to prevent the plate being jarred out of its true position as determined by the movement of the feed device, I provide friction blocks 66 held in suitable pockets 67 in the wall 42 and

resting upon the upper surface of the plate 47. In the pockets 67 above the blocks 66 I arrange compression springs 68 to hold the blocks 66 pressed against the upper face 5 of the feed plate 47 with a yielding pressure.

As many modifications of my invention will readily suggest themselves to one skilled in the art, I do not limit or confine my invention to the specific structures herein shown and described.

I claim:

1. In a device of the kind described, a gang punch mounted upon bearings to swing 15 up and down, a die device for holding a plurality of crowned nuts with their crowned ends facing the punch, the punch provided with forwardly projecting cutters, one for each nut, the cutters adapted 20 to swing freely into the bores of the nuts and cut notches therein by pressing outwardly against a suitable die, and pressure means individual to each nut adapted to firmly seat the nut on the die, substantially 25 as described.

2. In a device of the kind described, a punch holder mounted upon bearings to swing up and down, and carrying a plurality of horizontally spaced cutters projecting 30 forwardly therefrom, a die member adapted to support a like number of nuts with the crowned ends projecting towards the punch, the several cutters adapted to swing freely into the bores of the nuts and to cut notches 35 in the crowns thereof by pressing outwardly against the supporting die, and means for advancing the nuts from one cutter to another cutter and rotating them in such advancement so as to cut notches in the nuts 40 which advance around the crowns thereof step by step, substantially as described.

3. The combination with an ordinary punch press of a nut castellating device which consists of a punch member mounted 45 to swing up and down on bearings and provided with a plurality of cutters projecting from the forward side thereof, a die member for holding a like plurality of nuts, means for advancing the nuts from one position to 50 the next at each stroke of the press and for partially rotating the nuts in such advancement, and means for causing the punch member to swing up and down with the up and down movement of the press head, sub- 55 stantially as described.

4. In a device of the kind described, a gang punch comprising a holder mounted to swing up and down on a horizontal axis, transverse narrow slots in the holder opening through the top thereof for receiving thin elongated blades to serve as punches, and a single top plate secured to the holder and adapted to hold all of the blades in the holder, substantially as described.

5. In a device of the kind described, a

holder mounted to swing up and down on a horizontal axis, a plurality of horizontally spaced cutters carried by the holder, links at the ends of the holder connecting the holder to the head of a punch press, the 70 links each having a lost motion connection to the head, and a plunger carried by the head resting at its lower end upon the holder and adapted to push the holder down as the head descends, the plunger having a lost motion connection with the head 75 to permit the head a greater amplitude of motion than that of the holder, substantially as described.

6. The combination with a punch press 80 having a vertically movable head, of a gang punch device for castellating nuts, comprising a punch holder mounted on bearings to swing up and down, lost motion connection between the holder and the head and a lost 85 motion pressure member adapted to force the holder down when the head descends, a die having die slots arranged to receive the several punches and to hold crowned nuts with the crowned ends facing the punches, 90 a horizontally movable member for advancing the nuts from one position to another, and cam means operatively connecting said nut advancing member to the press head to cause the nuts to be advanced as the punch 95 head descends, substantially as described.

7. In a device of the kind described, a chute down which the nuts are fed, a horizontally movable feed member for moving the nuts from position to position, a swing- 100 ing member mounted on the device and operatively connected with the horizontally movable member for moving same back and forth, a cam bar rigid with the press-head, a cam projection on the horizontally swing- 105 ing member operatively connecting same with the cam bar and adapted to move the horizontally movable member back and forth as the press-head moves up and down, and means causing the nut engaging mem- 110 ber to move rearwardly out of engagement with the nuts on the backward movement and to move forwardly into engagement with the nuts on its forward movement and projections on the device in the path of the 115 nuts to cause them to rotate from face to face as they are advanced step by step through the device, substantially as described.

8. In a device of the kind described, a 120 gang punch mounted upon bearings to swing up and down, a die device for holding a plurality of crowned nuts with their crowned ends facing the punch, the punch provided with forwardly projecting cutters, 125 one for each nut, the cutters adapted to swing freely into the bores of the nuts and cut notches therein by pressing outwardly against a suitable die, and pressure means individually yieldable to each nut for firmly 130

seating the several nuts on the die, substantially as described.

9. In a device of the kind described, a gang punch mounted upon bearings to swing up and down, a die device for holding a plurality of crowned nuts with their crowned ends facing the punch, the punch provided with forwardly projecting cutters, one for each nut, the cutters adapted to 10 swing freely into the bores of the nuts and cut notches therein by pressing outwardly against a suitable die, and pressure means

individually yieldable to each nut for firmly seating the several nuts on the die, said pressure means having a projection in the 15 path of the nuts for rotating the nuts as they are moved from one position to the next, substantially as described.

Signed at Chicago, Illinois, this 20th day of March, 1920.

ARTHUR SPEAR.
